SEWING MACHINE

Robert A. Hayes, Franklin Park, Ill., assignor to
Union Special Machine Company, Chicago, Ill.,
a corporation of Illinois

Application July 29, 1950, Serial No. 176,565

14 Claims. (Cl. 112—214)

1

This invention relates to sewing machines and, in one of its more specific aspects, to a sewing machine adapted to be advantageously employed in the hemming of tubular articles such as leg bottoms of overalls and trousers, leg bottoms and sleeve ends of pajamas, and the like.

It is a primary object of the invention to provide a lock stitch sewing machine that is adapted to readily hem tubular articles and that has improved structural and operational characteristics.

Another object of the invention is to provide a sewing machine having a rotary hook with a hollow generally cylindrical means that serves as a throat plate and as a guard for the rotary hook.

Another object of the invention is to provide a sewing machine of the character indicated with a hollow, generally cylindrical throat plate that has a hook retainer disposed therein and that supports one of a pair of feed rollers which are adapted to advance a piece of work past the needle of the machine.

The invention has for another object, the provision of a throat plate of a type indicated that is adapted to be readily installed, removed and adjusted as required.

Another object of the invention is to provide an improved sewing machine work-feeding mechanism, including a pair of feed rollers and associated devices for imparting positive and intermittent rotation to the rollers, the parts being so constructed and arranged that both rollers are actuated at the same peripheral speed.

A further object of the invention is to provide a presser bar of a sewing machine of the type indicated with a yoke that carries one of the rollers of the work-feeding mechanism and pivotally supports a presser foot, means being provided to normally and yieldingly urge the presser foot in a direction toward the throat plate means about its pivotal connection with the yoke and additional means being provided for moving the presser foot in a reverse direction about its pivotal connection with the yoke in response to predetermined upward movement of the presser bar.

A still further object of the invention is to provide a sewing machine of the character indicated that is capable of performing its intended functions in a trouble-free and efficient manner.

To the end that the foregoing objects may be attained, a sewing machine, constructed in accordance with this invention, preferably comprises a frame including a base, a hollow standard, a hollow overhanging arm projecting later-

ally from the upper end of the standard and a hollow needle head secured to the free end of the overhanging arm.

The base is provided with a relatively narrow extension at its end remote from the standard and supports a rotary hook that projects beyond the free end of the extension. A hollow, generally cylindrical throat plate means, secured to the extension, circumscribes and is spaced from the rotary hook. The throat plate means may be of one piece construction or may consist of several pieces as will be described further along herein. Mounted within the throat plate means is a hook retainer. The throat plate means is provided with integral external lugs that have bearings for supporting a lower feed roller. The machine includes vertically reciprocable presser and needle bars. Secured to the lower end of the presser bar for reciprocation therewith is a yoke that includes a pair of downwardly and rearwardly extending arms. An upper feed roller is rotatively supported between the yoke arms about an axis parallel to the axis of the lower feed roller. A foot presser member is pivotally connected to the end portions of the arms and extends over and forwardly of the axis of the upper feed roller. Attached to the forward portion of the member is a presser foot having a needle receiving opening that is adapted to align with a needle bushing in the throat plate means. Resilient means are provided for normally and yieldingly urging the presser foot member in a direction toward the throat plate about its pivotal connection with the yoke arms. A stationary cam carried by the overhanging arm is adapted upon predetermined upward movement of the presser bar to move the presser foot member in a reverse direction about its pivotal connection with the yoke arms.

The feed rollers are arranged for positive and intermittent rotation at the same peripheral speed through the medium of an arrangement of devices operable in timed relation to reciprocation of the needle bar and rotation of the rotary hook. This arrangement of devices includes a one-way clutch mechanism, a rotary driving shaft, gear means responsive to rotation of the driving shaft, and a pair of driven shafts connected to the gear means and to corresponding feed rollers. The driven shafts are provided with universal joints, the driven shaft for the upper feed roller being adapted to compensate for movement of that roller occasioned by work of varying thickness passing between the rollers.

55 The enumerated objects, together with other

objects, as well as the advantages obtainable from the practice of this invention, will be readily understood by persons skilled in the art upon reference to the following detailed description, taken in conjunction with the annexed drawings, which respectively describe and illustrate preferred arrangements of devices constructed in accordance with the invention.

In the drawings:

Figure 1 is a view in front elevation of a sewing machine constructed in accordance with the invention, certain parts being broken away and other parts being shown in central vertical longitudinal section for better illustration;

Figure 2 is an enlarged bottom plan view of the major portion of the sewing machine shown in Figure 1, certain parts being broken away and other parts being shown in longitudinal section;

Figure 3 is an end view of Figure 1 in enlargement as seen from the left thereof, certain parts, such as cover plate and the needle, being omitted;

Figure 4 is a view in enlargement taken along line 4-4 of Figure 3;

Figure 5 is an enlarged view taken along line 5-5 of Figure 1, parts being omitted for better illustration;

Figure 6 is an enlarged view in elevation of the hook retainer shown in Figure 2;

Figure 7 is a view taken along line 7-7 of Figure 6;

Figure 8 is a view taken along staggered line 8-8 of Figure 5;

Figure 9 is a view in enlargement taken along line 9-9 of Figure 3;

Figure 10 is a front elevation view of the presser foot member;

Figure 11 is a view taken along line 11-11 of Figure 9;

Figure 12 is an enlarged isometric view of the hollow throat plate and hook retainer shown in Figures 1 and 2;

Figure 13 is a fragmentary view corresponding to a portion of Figure 5 and illustrating a folder operably mounted on the machine;

Figure 14 is similar to Figure 11 and illustrates a modified form of construction;

Figure 15 corresponds to Figure 12 and illustrates a modified form of throat plate means; and,

Figure 16 corresponds to a portion of Figure 3 and illustrates another modification of the throat plate means construction.

Referring now to the drawings wherein like reference numerals denote corresponding parts throughout the several views, the invention has been shown as applied to a lock stitch sewing machine that is similar in many respects to the machines disclosed in Christensen et al. Patent No. 2,113,572 entitled "Lock Stitch Sewing Machine," granted April 12, 1938, and Sauer Patent No. 2,324,598, entitled "Sewing Machine," granted July 20, 1943. The machine embodies a frame consisting of a base 20, having a planar top surface 21, a hollow vertical standard 22, rising from one end of the base, a hollow overhanging arm 23 extending laterally from the upper end of a vertical standard, and a hollow needle head 24 provided at the free end of the overhanging arm and having a removable cover plate 25. Base 20 has an integral and relatively narrow extension 26 that is grooved as indicated at 27 in Figure 5.

The machine is provided with a pair of rotary main shafts, namely, an upper main shaft 28

5 within the overhanging arm (Figure 1) and a lower main shaft 29 supported by the base beneath top surface 21 (Figures 1 and 2). These shafts are interconnected by a gear train 30 within the vertical standard. The upper main shaft is adapted to be driven from a suitable source through a combined handwheel and pulley 31 secured to its outer end. A needle bar 32, that carries a needle 33 at its free end, is mounted for vertical reciprocation in the needle head and is arranged to be driven by a needle driving mechanism 34 in response to rotation of the upper main shaft. Mechanism 34 is preferably the same as the corresponding mechanism shown in said Sauer patent.

Cooperating with needle 33 in the formation of stitches in a piece of work is a rotary hook 35 that is affixed to the outer end of an auxiliary rotary shaft 36 (Figure 2) which is supported by base 28 in parallel relationship to lower main shaft 29. Shaft 36 has a gear 37 which meshes with a gear 38 that is secured to and rotatable with the lower main shaft. Gears 37 and 38 are disposed in a gear housing 39 and are so related that a rotary component of rotary hook 35 is adapted to be rotated at twice the angular speed of shaft 29, as disclosed in said Christensen et al. patent. The rotary hook, as best shown in Figure 2, is positioned beyond the free end of base extension 26.

Reference is next had to Figures 2, 5 and 12, for an understanding of one recommended form of throat plate means 40, that is one of the features of the invention. Means 40 comprises a hollow, cylindrical member 41 having an integral extension 42 that is provided with a pair of slots 43. Also integral with member 41 is a pair of spaced bearing lugs or supports 44 that project rearwardly and upwardly therefrom. Lugs 44 carry coaxial sleeve bearings 45. When the machine is assembled extension 42 registers with groove 27 in extension 26 (Figure 5) and is secured thereto by screws 46 which extend through slots 43. As is best shown in Figure 2 cylindrical member 41 surrounds and is spaced from rotary hook 35 and is adjustable axially relative to the rotary hook as allowed by slots 43 and screws 46. Cylindrical member 41 has a front opening 47 to permit access to screw 46 of the rotary hook (Figure 2), and is provided with a vertically disposed needle bushing 50 that is aligned with needle 33.

In Figures 2, 6 and 7 there is shown a hook retainer that consists of a segmental member 51 and an integral inwardly projecting element or finger 52. The hook retainer is positioned wholly within cylindrical member 41 and is attached thereto by screw 53.

A lower feed roller 55 is affixed by a set screw 56 to a shaft 57 that is rotatable in bearings 45 (Figure 5). The roller is toothed or serrated peripherally as indicated at 58 in Figure 3 for better traction and is adapted to cooperate with another roller to be described further along herein in feeding work past the needle.

A presser bar 60 carried by and vertically reciprocable with respect to needle head 24 is normally urged downwardly by a compression spring 61 (Figure 3). An inverted generally U-shaped yoke 62 that includes a pair of spaced, parallel, downwardly and rearwardly projecting arms 63 is affixed to the lower end of the presser bar by a set screw 64. A shaft 65, parallel to shaft 57, is rotatively supported in coaxial sleeve bearings 66 carried by arms 63. Attached to and rotatable

with shaft 65 is an upper feed roller 67 that is toothed or serrated as indicated at 68. As is shown in Figure 3 roller 67 is directly above roller 55 and is urged toward roller 55 due to the action of spring 61 on the presser bar.

Feed rollers 55 and 67 are adapted to be rotated intermittently and in unison at the same peripheral speed by an arrangement of devices that will now be described, reference being had particularly to Figures 1, 5 and 8. The arrangement of devices includes a one-way clutch 10 that is preferably of the type disclosed in Schoij Patent No. 2,494,006, entitled "Clutch Mechanism for Sewing Machines," granted January 10, 1950, to which reference may be had for details of construction. The one-way clutch is driven by a means that is generally indicated by numeral 71 and that is similar to corresponding apparatus disclosed in Kucera Patent No. 2,265,605, entitled "Sewing Machine," granted December 9, 1941. Parts of means 71 are shown in Figure 8 and include a lever 72 connected to the one-way clutch and having an elongated slot 73. A ball pin 74 at the upper end of a pitman 75 is adjustable along slot 73 to vary the stroke of the lever 72. The pitman has a strap portion 76 which embraces an eccentric 77 that is secured to lower main shaft 29. It will be apparent from a consideration of Figure 8 that rotation of shaft 29 actuates the pitman in a manner to impart oscillatory movement to lever 72 thereby correspondingly actuating one-way clutch 10.

The one-way clutch includes a gear 80 (Figure 1) which meshes with a second gear 81 that is affixed by a set screw 82 to the inner end of a driving shaft 83 that is supported by clutch housing 84. A gear 85 is attached to the outer end of shaft 83 by a set screw 86. Gears 81 and 85 are arranged so as to permit of slight axial movement of shaft 83. A bracket 87 secured to the clutch housing supports a rotary shaft 88 that is parallel to shaft 83 (Figure 5). Rotary movement is imparted to shaft 88 by a gear 89 that meshes with gear 85.

Shaft 83 is connected to upper roller shaft 65 by a sectional shaft 90 (Figure 1) that consists of end sections 91 and 92 and an intermediate section 93 that forms universal joints with sections 91 and 92 as indicated at 94 and 95 respectively. Similarly shaft 88 is connected to lower feed roller shaft 51 by a sectional shaft 96 (Figure 5), that consists of end sections 97 and 98 and an intermediate section 99 that forms universal joints with sections 97 and 98 as indicated at 100 and 101.

A pin 103 is supported by the free end portions of yoke arms 63 and is secured to one of these arms by a set screw 104 (Figures 3 and 9). A presser arm member 105, best shown in Figures 3, 9 and 10, comprises a web 106 and a pair of upstanding arms 107 and 108 that are apertured to receive and form a pivotal connection with pin 103. Arm 107 projects above arm 108. On the other hand, arm 108 has an integral extension 109 that extends upwardly and forwardly over roller shaft 65 and thence downwardly and forwardly as illustrated in Figure 3. A horizontally disposed bar 110 is slideable axially with respect to yoke 62 (Figure 9), and has an elongated axial through slot 111. A pin 112 carried by the yoke extends through slot 111 and prevents angular movement but permits axial movement of the bar relative to the yoke. The bar has at its rearward end a laterally projecting stud 113 that bears against the rear edge of arm 107, and is

threaded at its forward end to receive a knurled adjusting nut 114. A compression spring 115 is coaxial with the bar, and bears at its opposite ends against the yoke and nut 114, to normally and yieldingly urge bar 110 toward the right, thereby urging presser foot member 105 in a clockwise direction about pin 103 as viewed in Figure 3.

A presser foot 116 is attached to the forward end of arm 109 by a stud 117. The presser foot has a slot 118 that aligns with throat plate bushing 50 and that receives needle 33 during operation. The free end of arm 109 may bear against the upper face of the presser foot as shown in Figure 11 thereby preventing pivotal movement of the presser foot relative to member 105. Alternatively, the end of arm 109 may be slightly spaced from the upper face of the presser foot, as indicated at 119 in Figure 14, thereby permitting limited pivotal movement of the presser foot with respect to that arm.

The illustrated sewing machine preferably includes a thread release mechanism 120 (Fig. 3) that comprises a link 121 pivotally connected at its lower end to stud 117 and at its upper end to a stud 122, that is attached to the lower end of a vertically reciprocable rod 123. A collar 124 is attached to the upper end of rod 123 by a set screw 125 and carries a generally L-shaped rod 126 that is adjustable laterally with respect to the collar by a set screw (not shown). Mechanism 120 is similar in construction, function and operation to the one disclosed in Christensen Patent No. 2,434,608 entitled "Sewing Machine," granted January 13, 1948, to which reference may be had.

Referring next to Figures 3 and 4, I have illustrated therein a means for swinging presser foot member 105 and therefore presser foot 116 in a counter clockwise direction as viewed in Figure 3, about pin 103, against the action of spring 115 in response to predetermined upward movement of presser bar 60. In this connection a presser bar lever 130 having a camming edge 131 is pivoted to needle head 24 by a stud 132. Camming edge 131 cooperates with a bracket 133 that is attached to the presser bar to move the presser bar upwardly against the action of spring 61 in response to clockwise movement of lever 130 as viewed in Figure 3. Another bracket 134 is affixed to the needle head by a screw 135 which extends through an elongated slot 136 that permits of horizontal adjustment of the bracket relative to the needle head. A cam member 137 having a camming surface 138 is attached to the rear of bracket 134 by a screw 139. As will be observed from an inspection of Figure 3, the upper extremity of arm 107 is adapted to ride along camming surface 138 upon predetermined upward movement of the presser bar, thereby swinging presser bar 105 in a counter clockwise direction against the action of spring 115. This effects raising of presser foot 116.

A bracket 140 is attached to base extension 26 by screws 141. A collapsible folder 142 (Figure 13) may be mounted on bracket 140 by screws 143. Folder 142 may be the same as or similar to the one disclosed in Chalman Patent No. 1,305,253, entitled "Hemmer for Sewing Machines," granted June 3, 1919.

For the purpose of briefly outlining the mode of operation of the embodiment of the invention shown in Figures 1 through 13, it is assumed that the parts are assembled and are in the relative positions shown in Figures 1 and 3. Combined

handwheel and pulley 31 is rotated by a suitable driving means that preferably consists of an electric motor and a drive belt (not shown). This imparts rotation to upper main shaft 28 and lower main shaft 29 thereby effecting reciprocation of needle bar 32 and needle 33 and rotation of rotary hook 35. Simultaneous therewith one-way clutch 70 is actuated by its driving means 71, thereby imparting intermittent rotation to driving shaft 83 which, by virtue of its interconnection with gears 85 and 89 and shaft 88, imparts corresponding rotation to sectional shafts 90 and 96, and thence to upper feed roller 67 and lower feed roller 55, respectively. Upper feed roller 67 is rotated in a clockwise direction while lower feed roller 55 is rotated in counter-clockwise direction, as viewed in Figure 3, in the course of operation. Compression spring 61 urges presser bar 60 downward so that a piece of tubular work to be hemmed by the machine is gripped and fed past the needle by the rollers. At the same time presser foot 116 is urged downwardly due to the action of spring 115. The arrangement shown in the drawing, including springs 61 and 115 permit the rollers and the presser foot to accommodate themselves to variations, due to seams and the like, in the thickness of the work being stitched. The slight axial movement permitted in shaft 83 compensates for vertical movement of the presser bar and upper feed roller.

Figure 15 illustrates a modified form of throat plate means 145 corresponding to earlier described throat plate means 40. Means 145 comprises upper and lower semi-cylindrical members 146 and 147 having corresponding hinge lugs 148 and 149 that are joined by a hinge pin 150. The semi-cylindrical members are maintained in the illustrated position by a spring detent that includes a leaf spring 151 affixed to lower member 147 by a screw 152 and having a kink 153 that registers with a groove 154 in number 146. This construction permits of ready access to the rotary hook for purposes of adjustment or repair without the necessity of removing the entire throat plate means from the base.

Another modification of the throat plate means is generally designated by numeral 155 in Figure 16, and comprises an arcuate upper member 156 having a pair of lugs 157, only one of which is shown. These lugs correspond to lugs 44 of the embodiment shown in Figure 12. Means 155 also comprises an arcuate lower member preferably made of sheet metal and having a lateral flange 159 that is secured to the underside of lugs 157 by screws 160. The throat plate means of Figure 16 is also provided with a hook retainer 161 that corresponds to hook retainer 51 of Figure 12.

Thus it will be seen that the constructions herein shown and described are well adapted to accomplish the objects of the present invention. It will be understood, however, that the invention may be embodied otherwise than as here shown, and that in the forms illustrated, certain obvious changes in construction may be made. Therefore, I do not wish to be limited precisely to the constructions herein shown except as may be required by the appended claims considered with reference to the prior art.

I claim:

1. In a sewing machine that includes a frame which carries vertically reciprocable presser and needle bars and a rotary hook adapted to cooperate with a needle secured to the needle bar

in the formation of stitches in a piece of work, a hollow throat plate secured to the frame and positioned in surrounding and spaced relation to the rotary hook, a retainer for the rotary hook attached to and disposed within the throat plate, a pair of substantially parallel feed rollers consisting of a first roller mounted on the throat plate and a second roller secured to the presser bar, a rotary roller driving shaft carried by the frame, means for imparting intermittent rotation to the driving shaft, first and second rotary shafts connected respectively to the first and second rollers, and means for simultaneously rotating the first and second shafts at the same peripheral speed in response to corresponding rotation of the driving shaft.

2. In a sewing machine that includes a frame which carries vertically reciprocable presser and needle bars and a rotary hook adapted to cooperate with a needle secured to the needle bar in the formation of stitches in a piece of work, a one-piece hollow and generally cylindrical throat plate secured to the frame and positioned in surrounding and spaced relation to the rotary hook, support means integral with and exterior the throat plate, a retainer for the rotary hook attached to and disposed within the throat plate, a pair of substantially parallel feed rollers consisting of a first roller mounted on the support means and a second roller secured to the presser bar, and means for imparting intermittent and simultaneous rotation to the rollers.

3. In a sewing machine that includes a frame which carries vertically reciprocable presser and needle bars and a rotary hook adapted to cooperate with a needle secured to the needle bar in the formation of stitches in a piece of work, a one-piece hollow and generally cylindrical throat plate secured to the frame and positioned in surrounding and spaced relation to the rotary hook, support means integral with and exterior the throat plate, a retainer for the rotary hook attached to and disposed within the throat plate, a pair of substantially parallel feed rollers consisting of a first roller mounted on the support means and a second roller secured to the presser bar, a rotary roller driving shaft carried by the frame, means for imparting intermittent rotation to the driving shaft, first and second rotary shafts connected respectively to the first and second rollers, and means for simultaneously rotating the first and second shafts at the same peripheral speed in response to corresponding rotation of the driving shaft.

4. In a sewing machine that includes a frame which carries vertically reciprocable presser and needle bars and a rotary hook adapted to cooperate with a needle secured to the needle bar in the formation of stitches in a piece of work, hollow throat plate means secured to the frame and positioned in surrounding and spaced relation to the rotary hook, said means comprising arcuate upper and lower members, the upper member being attached to the frame and the lower member depending from the upper member, a retainer for the rotary hook attached to the upper member and positioned within the throat plate means, a pair of substantially parallel feed rollers mounted respectively on the upper member and the presser bar, and means for imparting intermittent and simultaneous rotation to the rollers.

5. In a sewing machine that includes a frame which carries vertically reciprocable presser and

needle bars and a rotary hook adapted to cooperate with a needle secured to the needle bar in the formation of stitches in a piece of work, hollow throat plate means secured to the frame and positioned in surrounding and spaced relation to the rotary hook, said means comprising arcuate upper and lower members, the upper member being attached to the frame and the lower member depending from the upper member, support means integral with and exterior the upper member, a retainer for the rotary hook attached to the upper member and positioned within the throat plate means, a pair of substantially parallel feed rollers consisting of a first roller carried by the support means and a second roller carried by the presser bar, and means for imparting intermittent and simultaneous rotation to the rollers.

6. A sewing machine in accordance with claim 5 including a hinge connecting the upper and lower members and detent means releasably maintaining the lower member in predetermined angular position with respect to the upper member.

7. In a sewing machine that includes a frame which carries vertically reciprocable presser and needle bars and a rotary hook adapted to cooperate with a needle secured to the needle bar in the formation of stitches in a piece of work, hollow throat plate means secured to the frame and positioned in surrounding and spaced relation to the rotary hook, said means comprising an arcuate upper member attached to the frame, an arcuate lower member hingedly connected to the upper member, detent means releasably maintaining the lower member in predetermined angular position with respect to the upper member, support means integral with and exterior the upper member, a retainer for the rotary hook attached to the upper member and positioned within the throat plate means, a pair of substantially parallel feed rollers consisting of a first roller mounted on the support means and a second roller secured to the presser bar, a rotary roller driving shaft carried by the frame, means for imparting intermittent rotation to the driving shaft, first and second rotary shafts connected respectively to the first and second rollers, and means for simultaneously rotating the first and second shafts at the same peripheral speed in response to corresponding rotation of the driving shaft.

8. In a sewing machine that includes a frame which carries vertically reciprocable presser and needle bars and a rotary hook adapted to cooperate with a needle secured to the needle bar in the formation of stitches in a piece of work, a hollow throat plate secured to the frame and positioned in surrounding and spaced relation to the rotary hook, a yoke attached to and reciprocable with the presser bar, a pair of substantially parallel feed rollers consisting of a first roller mounted on the throat plate and a second roller carried by the yoke, means for imparting intermittent and simultaneous rotation to the rollers, a presser foot member pivotal with respect to the yoke about an axis that is rearward of the axis of the second roller, a presser foot attached to the presser foot member and positioned forward of the second roller, and resilient means normally and yieldingly urging the presser foot member in a direction toward the throat plate about its pivotal connection with the yoke.

9. In a sewing machine that includes a frame which carries vertically reciprocable presser and

needle bars and a rotary hook adapted to cooperate with a needle secured to the needle bar in the formation of stitches in a piece of work, a hollow throat plate secured to the frame and positioned in surrounding and spaced relation to the rotary hook, a yoke attached to and reciprocable with the presser bar, a pair of substantially parallel feed rollers consisting of a first roller mounted on the throat plate and a second roller carried by the yoke, a rotary roller driving shaft carried by the frame, means for imparting intermittent rotation to the driving shaft, first and second rotary shafts connected respectively to the first and second rollers, means for simultaneously rotating the first and second shafts at the same peripheral speed in response to corresponding rotation of the driving shaft, a presser foot member pivotal with respect to the yoke about an axis that is rearward of the axis of the second roller, a presser foot attached to the presser foot member and positioned forward of the second roller, and resilient means normally and yieldingly urging the presser foot member in a direction toward the throat plate about its pivotal connection with the yoke.

10. In a sewing machine that includes a frame which carries vertically reciprocable presser and needle bars and a rotary hook adapted to cooperate with a needle secured to the needle bar in the formation of stitches in a piece of work, a hollow throat plate secured to the frame and positioned in surrounding and spaced relation to the rotary hook, a yoke attached to and reciprocable with the presser bar, a pair of substantially parallel feed rollers consisting of a first roller mounted on the throat plate and a second roller carried by the yoke, means for imparting intermittent and simultaneous rotation to the rollers, a presser foot member pivotal with respect to the yoke about an axis that is rearward of the axis of the second roller, a portion of the presser foot member extending over and forwardly of the axis of the second roller, a presser foot attached to the presser foot member forward of the axis of the second roller, and resilient means normally and yieldingly urging the presser foot member in a direction toward the throat plate about its pivotal connection with the yoke.

11. A sewing machine in accordance with claim 8 including means responsive to predetermined upward movement of the presser bar for moving the presser member in a reverse direction about its pivotal connection with the yoke against the action of the resilient means.

12. A sewing machine in accordance with claim 11 wherein the means recited therein comprises a stationary camming element secured to the frame.

13. In a sewing machine that includes a frame which carries vertically reciprocable presser and needle bars and a rotary hook adapted to cooperate with a needle secured to the needle bar in the formation of stitches in a piece of work, a hollow throat plate secured to the frame and positioned in surrounding and spaced relation to the rotary hook, an inverted generally U-shaped yoke attached to and reciprocable with the presser bar, said yoke including a pair of spaced downwardly and rearwardly projecting arms, a pair of substantially parallel feed rollers consisting of a first roller mounted on the throat plate and a second roller carried by the yoke arms, means for imparting intermittent and simultaneous rotation to the rollers, a presser foot member carried by and pivotal with respect to the yoke arms

11

about an axis that is rearward of the axis of the second roller, a portion of the presser foot member extending over and forwardly of the axis of the second roller, a presser foot attached to the presser foot member forward of the axis of the second roller, and resilient means normally and yieldingly urging the presser foot member in a direction toward the throat plate about its pivotal connection with the yoke.

14. In a sewing machine that includes a frame which carries vertically reciprocable presser and needle bars and a rotary hook adapted to cooperate with a needle secured to the needle bar in the formation of stitches in a piece of work, a hollow throat plate secured to the frame and positioned in surrounding and spaced relation to the rotary hook, an inverted generally U-shaped yoke attached to and reciprocable with the presser bar, said yoke including a pair of spaced downwardly and rearwardly projecting arms, a pair of substantially parallel feed rollers consisting of a first roller mounted on the throat plate and a second roller carried by the yoke arms, a rotary roller driving shaft carried by the frame,

means for imparting intermittent rotation to the driving shaft, first and second rotary shafts connected respectively to the first and second rollers, means for simultaneously rotating the first and second shafts at the same peripheral speed in response to corresponding rotation of the driving shaft, and means responsive to predetermined upward movement of the presser bar for moving the presser foot member in a reverse direction about its pivotal connection with the yoke arms against the action of the resilient means, said last mentioned means comprising a camming element secured to the frame.

ROBERT A. HAYES.
